Attorneys

UNITED STATES PATENT OFFICE.

HUGH McC. DAVENPORT, OF LOS ANGELES, CALIFORNIA.

CIGARETTE HOLDER, DAMPER, AND PRESERVER.

Application filed May 10, 1926. Serial No. 107,968.

My invention is a cigarette holder and damper, a similar construction being adaptable for use with cigars.

An object of my invention is a cigarette holder and damper or snuffer, the snuffer being placed over the end of a cigarette or cigar and forming an air-tight seal, causing the cigarette or cigar to be extinguished and forming a burned or charcoaled end on the cigarette or cigar.

Another object of my invention is to provide the holder with a small pin or prong which engages the cigarette and retains it in the holder.

Another type of cigarette holder and damper is a case in which a cigarette without a holder mouthpiece may be inserted, this forming an air-tight closure and causing the snuffing out of the cigarette or cigar placed therein.

A main object of my invention is to provide a device by which a burning cigarette or cigar may be quickly damped or snuffed, by inserting the cigarette or cigar in an air-tight closure, the burning end of the cigarette or cigar causing the tobacco to char in a manner similar to forming a substance similar to charcoal and thereby sealing the end of the cigarette or cigar.

It is well known to smokers that cigarettes and cigars after burning out naturally and being lit again do not have the same taste or aroma of the original cigarette or cigar. Moreover, when cigarettes or cigars become extinguished in the natural manner by burning out, the cigarette or cigars become dried. Certain types of cigarettes moreover, have tobacco which will practically continuously burn, whether being smoked or not, and as smokers are frequently required to or wish to stop smoking, they must either throw away the cigarette or cigar when only partly smoked or pinch the end off or hold same until it becomes naturally extinguished, and as above mentioned some types of cigarettes and cigars do not naturally extinguish, but naturally keep burning.

I find that cigarettes and cigars when damped or snuffed by my type of device retain the same flavor and aroma as they had originally. This I judge is due to the sealing of the end of the cigarette or cigar by the charring thereof.

My invention will be more readily understood from the following description and drawings, in which;

Figure 1 is a side elevation of a cigarette holder with my damper or snuffer in position;

Fig. 2 is a longitudinal section;

Fig. 3 is a side elevation of a box-like holder and damper;

Fig. 4 is a longitudinal section of Fig. 3, indicating a cigarette placed therein;

Fig. 5 is a longitudinal section of a cigar holder with my damper or snuffer placed thereon;

Fig. 6 is a section similar to Fig. 4, of a case forming a cigar holder.

Referring first to the construction of Figs. 1, 2 and 5, a cigarette or cigar holder is designated generally by the numeral 1, having the mouth piece 2 and passage 3 for smoke therethrough. A socket 4 is constructed in the end opposite the mouth piece for insertion of a cigarette or cigar indicated by the numeral 5. It will be noted in Fig. 2, that the socket is cylindrical as indicated by the numeral 6, whereas in Fig. 5 it is tapered as indicated by the numeral 7 to conform to the shape of cigarettes and cigars.

A pin type of securing device is formed by a bar 8 having a prong 9 which extends radially through the aperture 10 into the socket. The bar 8 is preferably located in a groove 11 extending lengthwise of the cigarette or cigar holder. This bar is pivotally mounted on a transverse axis 12 and has a finger engaging end 13 by which the prong or pin may be retracted from the aperture and from the cigarette or cigar, in which the prong engages.

From the above construction it will therefore be seen that a cigarette or cigar mounted in my holder with the pin engaging such article prevents same from readily falling or dropping from the holder. The free end 13 of the bar having a prong, moreover, forms a device for preventing the holder end with the cigarette or cigar from rolling on a table or the like.

The damper or snuffer designated generally by the numeral 14 is a cap-like structure, preferably formed cylindrical with one closed end and the other open. The open end 15 has a suitable fit on the cigarette or

cigar holder. This is preferably a friction fit but may be any other suitable type of construction. For cigarettes the damper has preferably a spring clip 16 for engaging the pocket and if desired a chain 17 for securing the same to a person's clothing if desired.

The manner of using my holder and damper or snuffer as above described is believed obvious, however, it may be stated that as it is frequently desired to stop smoking a cigarette or cigar, after a portion of same has been consumed, the snuffer cap may be placed on the holder, even with the tobacco glowing and burning brightly. On account of the limited air supply the tobacco at the burning end quickly becomes charred, forming a species of charcoal. This seems to make a tight seal on the end of the cigarette or cigar, preserving the natural flavor and aroma of the tobacco. In order to continue smoking the cigarette or cigar, this charred end may readily be broken off and the cigarette or cigar re-lighted.

The receptacle holder and damper of Figures 3, 4 and 5 comprise a tubular structure 20 having an angular cut-out section 21 in which is fitted a hinged cover 22 having a partial end 23. This cover is designed to swing upwardly as indicated dotted by the numeral 24 of Fig. 3. The end 25 of the receptacle is closed and the end 26 registers with the end of the cover, thus forming a closure.

A cover form of spring for closing the cover is provided by attaching a leaf spring 27 by screws 28 or the like to part of the receptacle 20 and having the free end 29 slide through a yoke 30. A finger bar 31 is positioned on the opposite side of the pivot structure 32 to which the cover is secured, whereby the cover may be readily opened, it being apparent that the leaf spring will be bent in the reverse direction, thereby causing same to snap closed after a cigarette or cigar has been placed in the holder and damper, or removed therefrom.

It will be apparent that the holder and damper of Figs. 3, 4 and 6 is intended to be used for cigarettes or cigars when a smoker does not use a holder. The action is substantially the same as with the snuffer device of Figs. 1, 2 and 5, in that on account of the limited supply of air the burning cigarette or cigar quickly becomes charred at the end and may be re-lit breaking off the charred end.

Although my invention is of a simple character, it will nevertheless be apparent that it may be materially changed in general construction and in specific details to adapt it for different types of mouth pieces for cigarettes and cigar holders and that the receptacle type of construction may

also be materially altered. Such changes, however, would be within the spirit of my invention as set forth in the description, drawings and claims.

It is found that my damper or snuffer when used on cigarette or cigar holders practically eliminates the odor from such holders by closing the exposed end even when no cigarette or cigar is retained in the holder; thus reducing or eliminating the disagreeable feature of having the clothes smell of burnt tobacco by carrying such holders.

It is to be noted that the damper or snuffer is fitted on the circular end of the cigarette and cigar holder and forms an air-tight seal. The extreme end of the snuffer also functions to hold the pin type of securing device so that the prong may not be moved. Such ends extend over the groove 11 and prevents movement of the bar 8 and hence the prong 9 which extends through the aperture 10 into the cigarette or cigar.

By this construction the cigarette or cigar is always maintained attached to the cigarette or cigar holder and is ready for use when the snuffer is detached. Also the prong prevents loosening of the connection of the cigarette or cigar with their holders which allows air to get in the snuffer or damper which would carry on a slow combustion. Thus with my cigarette holder and damper there is a substantially air tight seal at the connection between the snuffer and the end of the mouthpiece and at the connection between the cigarette or the cigar and the socket of the mouthpiece.

It will also be noted that with my holder and snuffer, that the risk of fire is materially reduced and that economy is effected in the use of tobacco on account of the smoker not discarding partly smoked cigarettes.

Having described my invention, what I claim is:

1. A cigarette holder, damper and preserver, comprising in combination a holder having a mouth piece with a socket and a smoke passage from the socket to the mouth piece, there being a longitudinal groove in the outside of the mouth piece terminating in an aperture extending from said groove to the socket, said aperture being spaced from the outer end of the holder, a bar pivotally mounted to fit in said groove and having a prong to extend into the aperture, the bar terminating in one direction at the prong, the exterior surface of the holder between the prong and the end thereof being smooth, a tubular damper closed at one end and open at the other, the open end being fitted over the holder on the smooth outer end thereof forming an air tight seal and extending partly over the bar and retain-

ing the prong in the aperture to hold a cigarette in the holder and centrally positioned in the damper.

2. A cigarette holder, damper and server comprising in combination a holder having a mouth piece and a socket with a smoke passage therebetween, there being a longitudinal groove in the outside surface of the holder terminating in a transverse aperture leading from the groove to the socket, the aperture being spaced from the end of the holder, the outside surface at the end being smooth, a bar mounted on a pivot, said pivot being at the end of the groove towards the mouth piece and having

a finger end extending out of the groove, a prong on the bar extending through the aperture, the bar terminating at the prong, and a tubular damper closed at one end and open at the other, the open end fitting on the smooth exterior of the holder forming an air tight seal and engaging the bar to prevent movement of same and to retain the prong in the aperture, said prong being adapted to retain the cigarette in the socket centered in the damper.

In testimony whereof I have signed my name to this specification.

HUGH McC. DAVENPORT.
